ELECTRIC SWITCH

Sterling G. Sears, Garden City, N. Y.

Application December 3, 1943, Serial No. 512,687

12 Claims. (Cl. 200—67)

This invention relates to electric switches and more particularly to hand operated multiple position switches for successively operating a plurality of contacts.

An object of the invention is to provide a switch of the above type in which various sets of contacts are successively operated with a snap action in response to predetermined increments of operating pressure.

Another object is to provide a novel and improved switch of the above type which requires a predetermined pressure for operation, but which may be held in operated position by a substantially smaller pressure.

Another object is to provide a switch of the above type in which the operating pressures may be preselected and controlled in accordance with the operating requirements.

Another object is to provide a switch of the above type having novel and improved details of construction and features of operation.

Various other objects and advantages will be apparent as the nature of the invention is more fully disclosed.

In the drawings,

Fig. 1 is a top plan view of my switch mechanism with the top casing section removed to expose the operating parts;

Fig. 2 is a partial plan view similar to Fig. 1 showing the switch in the first operated position with one of the contacts closed;

Fig. 3 is a transverse section taken on the line 3—3 of Fig. 2;

Fig. 4 is a partial detail view of the switch in fully operated position with both contacts closed;

Fig. 5 is a top plan view similar to Fig. 1 showing a modified form of switch;

Fig. 6 is a partial plan view similar to Fig. 1 showing a further modified form of switch involving four sets of contacts;

Fig. 7 is a transverse section taken on the line 7—7 of Fig. 6; and

Fig. 8 is a detail view in perspective of the spring frame.

In accordance with the present invention, I provide a plurality of springs which are connected to be successively operated in response to progressive increments of pressure on the operating arm or button. Each spring is designed to operate with a snap action with a predetermined operating pressure and a predetermined holding pressure, which may be substantially less than the operating pressure. In certain instances the spring may be set to remain flexed until manually released, in which event, no holding pressure

will be required. The operating pressure of the spring is determined by the characteristics of the spring, by the point of application of operating pressure, and by the nature of the abutments.

5 In one embodiment each of the springs, with the exception of the last, is mounted on a movable frame which exerts pressure on the succeeding spring. When the spring having the lowest pressure response has been operated, its operating member bears against a stop, which thereafter causes the spring and its supporting frame to move as a unit and to apply operating pressure to the next succeeding spring, and so on until the entire series of springs has been operated.

10 Each spring comprises a bowed lead held under compression with its ends in fixed abutments so that transverse pressure causes the spring to flex past its center position with a snap action. The shape of the spring, the character of the abutments and the point of application of the pressure are controlled in a manner to be described so as to obtain the desired operating characteristics.

15 More specifically, the spring is bent to have two arms of unequal length and the pressure is applied in such a manner that the longer arm flexes as the spring snaps past its center or snap over position, the angularly disposed shorter arm forming, in effect, a movable abutment for the 20 longer arm which facilitates the operation.

The present switch is particularly useful in instances where it is desired to selectively close a plurality of circuits without danger of over-control. The switch, may, for example, be used 25 in a combination radio transmitter and receiver with the first contact set to energize the receiver and the second contact set to energize the transmitter. The operator would apply sufficient pressure to close the first contact when receiving and 30 would apply additional pressure to close the second contact when talking into the transmitter. The switch may also be used for gun fire control with the first contact, for example, set to control the firing of tracers and the second contact set 35 to control the firing of ammunition. Various other uses will be readily apparent as the nature of the invention is disclosed.

40 Referring to the drawings more in detail, the invention is shown in Figs. 1, 2 and 3 as applied 45 to a two-position, hand-operated switch comprising a base 10 which supports the various elements of the switch mechanism and forms a part of the housing therefor. The switch mechanism 50 comprises a pair of spring contact arms 11 mounted by suitable means shown as screws 13

on a boss 12 formed on the base 10, and cooperating fixed contact arms 14 mounted by means shown as screws 16 on bosses 15. Bosses 15 also carry connector strips 17 to which leads 18 are secured by suitable means shown as clips 19 which are connected to the connector strips 17 by means of screws 20. The leads 18 extend through a ferrule 21 in the base 10 into a cable 22.

The spring arms 11 carry clips 25 by means of which connection is made to leads 26 which are connected to terminal pins 27 secured in the base 10 and extending into a recess 28 which is adapted to receive a suitable connector jack. In the embodiment shown, a through connection is made from the cable 22 by means of a lead 30 connected to a terminal pin 31 located in the recess 28. One of the spring arms 11 is also shown as connected to a lead 32 which enters the cable 22. It is to be understood, of course, that the connections to the various contact strips will depend upon the particular circuits in which the switch is to be used and that the above are shown only by way of illustration.

The spring contact arms 11 and the fixed contact arms 14 carry contacts 35 and 36 respectively (Fig. 3). In the embodiment shown, these contacts are adapted to be closed when the arms 11 are flexed into their upper positions and to be opened when the arms 11 are flexed into lower positions, although the position may be reversed to cause the contacts to open when the arms are flexed upwardly.

For actuating the arms 11 there is provided a pin 38 which extends transversely of the base 10 beneath the arms 11 in a suitable groove or recess formed in said base. The pin 38 is provided with recesses 39 in registration with the various spring arms 11 and dimensioned to allow the spring arms to rest therein with the contacts in open position. Each recess 39 is formed with a sloping cam surface 40 which is adapted to raise the corresponding spring arm 11 into contact closing position in response to suitable longitudinal movement of the pin 38. In the embodiment shown the spring arms 11 are made with a circular cross-section as shown in Fig. 3 suited to ride up on the cam surfaces 40 for the above purpose. The cam surfaces 40 which the respective spring arms 11 engage are offset with respect to each other so that one of the contacts, shown in the drawings as the lower contact, closes when the pin 38 reaches a first operated position and the second contact closes when the pin 38 reaches a second operated position.

Fig. 1 shows the pin 38 in its upper position with both spring arms 11 in their corresponding recesses and both contacts open. Figs. 2 and 3 show the pin 38 in its first operated position with the lower spring arm 11 riding up on its cam surface 40 and the lower contact closed, but with the upper contact still open. In response to further longitudinal movement of the pin 38 to the position shown in Fig. 4, the upper contact is closed as its arm also rides up on the cooperating cam surface.

The positions of the pins 38 are controlled by a pair of snap action springs 45 and 46 which are mounted in a recess 47 in the base 10. Each of these springs 45 and 46 comprises a bowed leaf spring having a bend or curve at a point 45C, 46C respectively, displaced from the center thereof so as to form unequal spring arms 45A, 45B and 46A,

46B respectively. At the points 45C and 46C the spring is preferably bent with a smooth curve so as to avoid sharp corners or deflections which might tend to cause breakage. The spring 45 is formed with a slight bend 45D near the end of its longer arm 45A which may be varied for adjusting the compression of the spring. The spring 46 may be similarly formed if desired.

In the embodiment shown, the spring 45 is mounted in fixed abutments 55 and 56 formed in the base 10 with the abutment 55 slightly elevated with respect to the abutment 56 and carrying the shorter arm 46B.

The spring 45 is mounted on fixed abutments 60 and 61 in an open frame 62 having side walls 63 and end walls 64. The end walls 64 are shown as tapering inwardly and at their bottom edges 65 making a line contact with the lower spring 46 on which they rest. The taper of the walls 64 is such that the line contacts 65 are applied to the lower spring 46 at predetermined positions in accordance with the pressure to which the spring is to respond. The frame 63 is provided with a cross piece 66 forming a stop which is engaged by the spring 45 when in its lower or flexed position. A wall 67 of the base 10 forms a similar stop to limit the movement of the spring 46.

The spring 45 is positioned to be engaged by the pin 38 at a point determined by the pressure response requirements of the spring. The abutments 60 and 61 are so disposed with respect to the abutments 55 and 56 and the corresponding springs that the arms 45A of the spring 45 which is engaged by the pin 38 extends about

35 normal to the pin.

The pin 38 is actuated by an operating bar 70 having end flanges 71 which engage recesses 72 in the base 10 and are freely movable with respect thereto so that the pin 38 may be actuated by applying pressure to any portion of the operating bar. It is to be understood, of course, that the operating bar may be hinged at one end if desired or, in certain instances, may be replaced by an operating knob, as shown in Fig. 5.

Suitable bosses 74 may be formed on the base 10 adjacent the lower end of the pin 38 for guiding the same and preventing transverse movement. The entire device may be closed by a suitable cover 75, as shown in Fig. 3.

In the operation of this device, the pin 38 is normally in elevated position with both contacts open, as shown in Fig. 1. Upon the application of pressure to the bar 70 no movement takes place until sufficient pressure is applied to overcome the resistance of the spring 45. At this point the spring 45 flexes with a snap action to the position shown in Fig. 2, thereby causing the pin 38 to move to its first operated position at which the lower contacts are closed.

After the spring 45 has thus been brought against its stop 66, the spring 45 and the frame 63 thereafter move as a unit and apply pressure to the lower spring 46 at the points of line contact 65. When the pressure on the bar 70 has been increased sufficiently to overcome the resistance of the spring 46, this spring likewise flexes with a snap action to the position shown in Fig. 4 and engages the wall 67 of the base. This action permits movement of the pin 38 to its second operated position for the second pair of contacts.

The force which is required for actuating each of the springs may be determined by the material and dimensions of the springs, the positions of the abutments and the point of application of

force. The abutments may, of course, be made adjustable as shown in Fig. 5 if desired.

In the embodiment shown the spring 46 requires more pressure for its operation than the spring 45 because the line contacts 65 apply pressure to the spring 46 near the fixed ends thereof, whereas the pin 38 applies pressure to the spring 45 near its center. A differential action may thus be obtained even when springs having substantially identical characteristics are used. The difference in operating pressures is preferably made sufficiently great so that accidental operation is avoided and the danger of an accidental follow through from one spring to the other is avoided.

In the above type of spring the holding pressure may be adjusted independently of the actuating pressure by suitable variation of the position of the stop means and the location of the abutments. As the flexing movement of the spring is restricted the holding pressure increases, whereas if the spring is allowed to flex sufficiently while restrained by suitably fixed abutments a point is reached where the spring automatically maintains its flexed position without any holding force. The adjustment is preferably such that a substantial force is required to actuate the spring but a minimum holding force is needed, so as to eliminate the danger of accidental operation and at the same time avoid fatigue when the contact is to be held closed for a substantial length of time.

The provision of spring arms of unequal lengths improves the operation of the device and permits a fine control of the operating characteristics to be obtained.

Referring now to the embodiment of Fig. 5, the features which correspond to those of Figs. 1 to 4 have been given the same reference characters and will not be redescribed. In this embodiment the connector pins 27 and 28 have been omitted inasmuch as all of the leads are shown as taken through the cable 22. This switch is designed to be attached to the end of the cable whereas the previous embodiment is designed to be attached to an intermediate portion of the cable. Also the operating bar 10 has been replaced by a knob 80 merely by way of illustration.

The arrangement of the springs 45 and 46 of Fig. 5 is similar to that described above. In Fig. 5, however, the spring 46 is designed to operate first and when operated to retain its operated position until manually released. Consequently, it is not necessary to apply holding pressure after the spring has been actuated. In order to release the spring 46 of Fig. 5 a pin 81 is provided, having a cam surface 82 which is adapted to engage beneath the spring 46 and return the same to its original position. The pin 81 extends through the base 10 and is provided with an accessible operating knob 83. A spring 84 is provided for normally holding the pin 81 in its outer position.

A screw 85 is shown as bearing against the end of the spring 46 to form an adjustable abutment therefor. A similar screw 86 may be provided in the end wall 64 of the frame 63 to engage the end of the spring 45. By suitable adjustment of the screws 85 and 86, the operating characteristics of the springs may be varied as desired and the device may be adjusted in accordance with the use to which the switch mechanism is to be applied.

In the embodiment shown in Fig. 5 after sufficient pressure has once been applied to actuate

the spring 46 it remains in its actuated position. The spring 45 may then be actuated and released repeatedly without further actuation of the spring 46. When it is desired to again open both contacts and restore the original position of the springs, the knob 83 is pressed to release the spring 46 and return the same to its original position.

This embodiment may be useful, for example, in combined transmitters and receivers where it is desired to maintain the apparatus operative without manual attention but to close the transmitter circuit at intervals for talking. At the termination of the operation the apparatus may be again rendered inoperative by actuation of the knob 83.

In the embodiment of Figs. 6 and 7 the invention is applied to a switch having four contacts and four operating positions. In this embodiment the pin 100 corresponds to the pin 38 of Figs. 1 to 4 and is adapted to successively operate a plurality of switch arms 101 which correspond to the switch arms 11 of Fig. 1. Cooperating switch arms 102 correspond to the arm 14 of Fig. 1. While only three pairs of contacts have been shown, it is to be understood that any number of contacts may be used, dependent upon the number of springs which are to be successively operated. In the embodiment of Figs. 6 and 7, the pin 100 bears against a spring 110 which is held in a frame 111, the arrangement of the spring 110 and frame 111, being similar to that of the spring 45 and frame 63 above described. The frame 111 rests on a second spring 112 which is held in a second frame 113. The latter frame rests on a third spring 114 held in a frame 115. The frame 115 rests on a spring 116 which is held in abutments 117 and 118 in the base 120.

It is assumed that the spring 110 is designed to operate first. Thereafter, this spring and its frame 111 operate as a unit to apply pressure to the spring 112, which is designed to operate at a predetermined additional pressure. The spring 112 in turn, after operation, forms a unit with its frame 113, which then applies pressure to the spring 114, which is designed to operate in response to a predetermined further increase in pressure. When this spring operates its frame 115 applies pressure to the spring 116 and causes the latter to operate. In this way any desired number of contacts can be successively closed by the application of predetermined increments in pressure. While four springs have been disclosed above, it is to be understood that the number of springs may be varied in accordance with the number of contacts to be successively operated.

Although certain specific embodiments of the invention have been shown for purposes of illustration, it is to be understood that the invention is not to be restricted thereto but that various changes and modifications may be made therein as will be readily apparent to a person skilled in the art. The invention is only to be limited in accordance with the following claims.

What is claimed is:

1. A spring assembly comprising a leaf spring member, fixed abutments holding the ends of said spring member against spreading movement with the spring member bowed, a frame resting on said spring member to apply flexing pressure thereto, a second leaf spring carried in said frame, fixed abutments in said frame holding the ends of said second member against spreading movement with the second spring member bowed, and means applying flexing pressure to said sec-

ond spring member to cause the same to flex past its center position with a snap action, said second spring member being arranged to move as a unit with said frame to transmit flexing pressure to said first spring member for causing the latter to flex with a snap action, whereby said springs are operated successively in response to predetermined increments of pressure on said second spring member.

2. A spring assembly comprising a leaf spring member, fixed abutments holding the ends of said spring member against spreading movement with the spring member bowed, a frame having spaced end supports resting on said spring member at points near the ends thereof to apply flexing pressure thereto, a second leaf spring carried in said frame, fixed abutments in said frame holding the ends of said second member against spreading movement with the second spring member bowed, and means applying flexing pressure to said second spring member to cause the same to flex past its center position with a snap action, said second spring member being arranged to move as a unit with said frame to transmit flexing pressure to said first spring member for causing the latter to flex with a snap action, whereby said springs are operated successively in response to predetermined increments of pressure on said second spring member.

3. A spring assembly comprising a leaf spring member, fixed abutments holding the ends of said spring member against spreading movement with the spring member bowed, a frame resting on said spring member to apply flexing pressure thereto, a second leaf spring carried in said frame, fixed abutments in said frame holding the ends of said second member against spreading movement with the second spring member bowed, and means applying flexing pressure to said second spring member to cause the same to flex past its center position with a snap action, said second spring member being arranged to move as a unit with said frame to transmit flexing pressure to said first spring member for causing the latter to flex with a snap action, whereby said springs are operated successively in response to predetermined increments of pressure on said second spring member, each of said spring members having a bend at an intermediate portion thereof dividing the member into two angularly disposed spring arms of unequal length.

4. A snap action spring comprising a leaf spring member having a bend at an intermediate portion dividing the leaf spring member into two angularly disposed spring arms of unequal length, fixed abutments supporting the two ends of said spring member and securing the same against spreading movement when transverse pressure is applied, a frame having spaced end supports resting on said spring member at points near the ends thereof to apply flexing pressure thereto, a second leaf spring member similar to said first spring member carried in said frame, fixed abutments in said frame holding the ends of said second spring member against spreading movement with the second spring member bowed, and means applying flexing pressure to said second spring member to cause the same to flex past its center position with a snap action, said second spring member being arranged to move as a unit with said frame to transmit flexing pressure to said first spring member for causing the latter to flex with a snap action, whereby said springs are operated successively in response to predeter-

mined increments of pressure on said second spring member.

5. In an electric switch, a pair of spring contact arms, a pin mounted for longitudinal movement beneath said arms and having means operable in predetermined positions of said pin to successively operate said contact arms, and means actuated by longitudinal pressure on said pin to cause said pin to assume said predetermined positions with snap actions.

6. In an electric switch, a pair of spring contact arms, a pin mounted for longitudinal movement beneath said arms and having means operable in predetermined positions of said pin to successively operate said contact arms, and means actuated by longitudinal pressure on said pin to cause said pin to assume said predetermined positions with snap actions, said last means comprising a pair of leaf springs, abutments holding the ends of said springs against spreading movement with both springs bowed for flexing with a snap action, means applying pressure from said pin to one of said springs for flexing the same with a snap action and means transferring pressure from said first spring to the second spring for flexing the second spring with a snap action.

7. In an electric switch, a pair of spring contact arms, a pin mounted for longitudinal movement beneath said arms and having means operable in predetermined positions of said pin to successively operate said contact arms, and means actuated by longitudinal pressure on said pin to cause said pin to assume said predetermined positions with snap actions, said last means comprising a pair of leaf springs, abutments holding the ends of said springs against spreading movement with both springs bowed for flexing with a snap action, means applying pressure from said pin to one of said springs for flexing the same with a snap action, a frame carrying the abutments of said first spring, said frame resting on said second spring and having means transferring pressure thereto for flexing said second spring with a snap action.

45 8. In an electric switch, a pair of spring contact arms, a pin mounted for longitudinal movement beneath said arms and having means operable in predetermined positions of said pin to successively operate said contact arms, and means actuated by longitudinal pressure on said pin to cause said pin to assume said predetermined positions with snap actions, said last means comprising a pair of leaf springs, abutments holding the ends of said springs against spreading movement with both springs bowed for flexing with a snap action, means applying pressure from said pin to one of said springs for flexing the same with a snap action and means transferring pressure from said first spring to the second spring for flexing the second spring with a snap action, each of said spring members having a bend at an intermediate portion thereof dividing the member into two angularly disposed spring arms of unequal length.

65 9. In an electric switch, a pair of spring contact arms, a pin mounted for longitudinal movement beneath said arms and having means operable in predetermined positions of said pin to successively operate said contact arms, and means actuated by longitudinal pressure on said pin to cause said pin to assume said predetermined positions with snap actions, said last means comprising a pair of leaf springs, abutments holding the ends of said springs against spreading movement with both springs bowed for flexing with a snap action, means applying pressure from said pin to

one of said springs for flexing the same with a snap action, means transferring pressure from said first spring to the second spring for flexing the second spring with a snap action, and means adjusting the position of said abutments for controlling the characteristics of said springs.

10. In an electric switch, a pair of spring contact arms, a pin mounted for longitudinal movement beneath said arms and having means operable in predetermined positions of said pin to successively operate said contact arms, and means actuated by longitudinal pressure on said pin to cause said pin to assume said predetermined positions with snap actions, said last means comprising a pair of leaf springs, abutments holding the ends of said springs against spreading movement with both springs bowed for flexing with a snap action, means applying pressure from said pin to one of said springs for flexing the same with a snap action, means transferring pressure 20 from said first spring to the second spring for flexing the second spring with a snap action and manual release means engaging one of said springs when in a flexed position for restoring the same.

11. A multiple snap switch comprising a plurality of spring switch arms carrying contacts, a pin slidable with respect to said arms and having surfaces engaging the same to cause successive operation thereof in different positions of said pin, a number of normally bowed leaf springs corresponding to the number of switch arms, fixed abutments securing the ends of one of said springs against spreading movement, separate frames carrying the others of said springs, each frame having abutments securing the ends of its spring 25

against spreading movement and having surfaces resting on the adjacent spring, said pin having means engaging one of said springs to flex the same with a snap action, each frame in turn transferring pressure to the next spring to flex the same with a snap action, said springs having characteristics to cause successive operation in response to predetermined increments of pressure on said pin and determining the successive positions of said pin.

12. A multiple snap switch comprising a plurality of spring switch arms carrying contacts, a pin slidable with respect to said arms and having surfaces engaging the same to cause successive operation thereof in different positions of said pin, a number of normally bowed leaf springs corresponding to the number of switch arms, fixed abutments securing the ends of one of said springs against spreading movement, separate frames carrying the others of said springs, each frame having abutments securing the ends of its spring against spreading movements and having surfaces resting on the adjacent spring, said pin having means engaging one of said springs to flex the same with a snap action, each frame in turn transferring pressure to the next spring to flex the same with a snap action, said springs having characteristics to cause successive operation in response to predetermined increments of pressure 30 on said pin and determining the successive positions of said pin, and stop means on each frame to cause the frame and spring to move as a unit when its spring is flexed.

STERLING G. SEARS.
